CLAIM

The ornamental design for an arched cookware handle, as shown and described.

DESCRIPTION

FIG. 1 is an enlarged perspective view from above the arched cookware handle showing my new design;

FIG. 2 is a top plan view thereof;

FIG. 3 is a front elevation thereof;

FIG. 4 is a side elevation view thereof;

FIG. 5 is a bottom plan view thereof;

FIG. 6 is back elevation view thereof; and,

FIG. 7 is an enlarged perspective view from below thereof.

The pair of circular rivet holes in the flange portion of the handle, which are visible at least partially in FIGS. 1-4 and 6-7, are functional elements and are not intended to be limiting the scope of the ornamental design, forming no part thereof as claimed.
